DISPLAY RACK

Ernoll Wayne La Barre, Lombard, Ill., assignor to
W. L. Stensgaard and Associates, Inc., a corporation of Illinois

Application December 24, 1952, Serial No. 22,869

Term of patent 14 years

(Cl. D80—9)

To all whom it may concern:

Be it known that I, Ernoll Wayne La Barre, a citizen of the United States, residing in Lombard, in the county of Du Page and State of Illinois, have invented a new, original, and ornamental Design for a Display Rack, of which the following is a specification forming part thereof.

The dominant features of my design reside in the portions shown in full lines.

I claim:

The ornamental design for a display rack, as shown and described.

ERNOLL WAYNE LA BARRE.
